CLAIM

The ornamental design for a headlight as shown and described.

DESCRIPTION

FIG. 1 is a front, bottom, and right perspective view of a headlight showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, top, and right perspective view thereof;

FIG. 9 is an exploded top plan view of the headlight;

FIG. 10 is an exploded bottom plan view of the headlight;

FIG. 11 is an enlarged detail view of area 11 circumscribed within FIG. 3; and,

FIG. 12 is an enlarged detail view of area 12 circumscribed within FIG. 8.

The broken lines shown in the drawings represent portions of the headlight that form no part of the claimed design. The dot-dash broken lines encircling an enlargement portion of the design forms no part of the claimed design.

1 Claim, 12 Drawing Sheets
